UNITED STATES PATENT OFFICE.

EMIL GUY FOX, OF KENOSHA, WISCONSIN.

GAGE.

1,173,789.

Specification of Letters Patent. Patented Feb. 29, 1916.

Application filed March 16, 1914. Serial No. 824,932.

To all whom it may concern:

Be it known that I, EMIL G. FOX, a citizen of the United States, and a resident of Kenosha, in the county of Kenosha and 5 State of Wisconsin, have invented a new and useful Improvement in Gages, of which the following is a specification.

My invention is an improvement in gages, and has for its object to provide a device of 10 the character specified, for use in obtaining measures of distances between fixed points, wherein a support is provided having indicators mounted for movement toward and from each other, each indicator having 15 means whereby it may be secured rigidly to the support.

In the drawings:—Figure 1 is a front elevation of the improved gage, Fig. 2 is a perspective view of one of the indicators, 20 and Fig. 3 is a section on the line 3—3 of Fig. 1, looking in the direction of the arrows. Fig. 4 is a sectional view on the line 4—4 of Fig. 1.

The present embodiment of the invention 25 comprises a support 1, in the form of a bar of wood or the like, of rectangular cross section and of suitable length. A pair of indicators is mounted on the bar for movement toward and from each other, and each 30 indicator comprises a sleeve 2, and blade 3, the former being shaped to fit over the bar and to be capable of movement thereon.

The sleeve is of considerable length in order that it will not rock or move laterally 35 on the bar, and at its front face the sleeve is provided with a lateral extension 3. The extension is provided at the edge remote from the sleeve with graduations 4, and it will be noted that the inner end of the extension when the sleeve is in place, is flush with one face of the bar. That is, the scale or 40 measure formed by the extension extends from one face of the bar, across the bar and beyond the bar at the opposite side.

45 The sleeve is provided in the face adjacent to the extension with an internally threaded boss 5, and a set screw 6 is threaded through the boss for engaging the bar 1 to hold the sleeve in adjusted position. The 50 extension 3 is in the present instance, inte-

gral with the sleeve, although it is obvious that it is not necessarily so.

In practice two indicators are arranged on the bar, one near each end, and the indicators are oppositely arranged so that the extensions 3 of the sleeves are both at the outer ends of the sleeves. In use, the bar 1 will also be provided with graduations on the same scale as those of the extension 3.

The gage is used chiefly for measuring or 60 framing window openings, that is to say, for determining the height of such openings from the floor both at their top and bottom edges. For this purpose the implement is applied as shown in Fig. 1, the bar 1 in 65 such case lying in contact with the stud α and the blades or extensions 3 of the indicators project laterally across the face of the stub. It will be understood that before the implement is thus applied the two indicators 70 are adjusted on the bar 1 at such distance apart as required to define the length of the prospective window opening, and also its height above the floor. Thus when the implement is set alongside the stud α , the latter 75 is marked transversely with a pencil, the marks thus formed extending along the graduated edges of the blades 3.

It is apparent that the implement enables the use of a carpenter's square—which is 80 usually employed for this purpose—to be disposed of and thus time is saved and greater accuracy obtained.

I claim:—

A gage for carpenters' use, comprising a 85 straight, graduated bar and two metal indicators applied thereto, and each consisting of a sleeve fitting the bar slidably and provided with a clamp-screw and having a lateral extension in the form of a flat, gradu- 90 ated blade with straight and parallel upper and lower edges, said extensions being formed integrally with the sleeve and in the same plane with the front face thereof, as and for the purpose specified.

EMIL GUY FOX.
